FREDERIK E. KNOBLOCK, OF WORCESTER, MASSACHUSETTS, ASSIGNOR TO THE GRATON & KNIGHT MANUFACTURING COMPANY, OF WORCESTER, MASSACHUSETTS, A CORPORATION OF MASSACHUSETTS.

WORK-SUPPORT FOR SEWING-MACHINES.

1,300,848.

Specification of Letters Patent. Patented Apr. 15, 1919.

Application filed June 6, 1918. Serial No. 238,431.

To all whom it may concern:

Be it known that I, FREDERIK E. KNOBLOCK, a citizen of the United States, residing at Worcester, in the county of Worcester and State of Massachusetts, have invented a new and useful Work-Support for Sewing-Machines, of which the following is a specification.

This invention relates to a device for holding the work while being operated upon by a sewing machine. More specifically it relates to a device on which a hollow article of leather is placed in order that its corner seam may be sewed on a sewing machine, the same being capable of moving as may be necessary in order to permit of the seam being sewed entirely around the article whatever its shape may be.

Heretofore leather articles, such as circular, square, and other shaped covers and boxes and the like, have usually been held in the hands of the operator while having their corner seams sewed and have been hand guided throughout the course of the operation. By this invention the article is simply placed on a block of the proper shape and the seam started. The block has to turn with the article as the sewing of the seam proceeds and is so restricted in its motion that while it is free to move in the proper direction it must follow the shape of the article and a completed seam can be sewed which is more even than any that can be sewed by the most skilled operators, and yet in the case of a comparatively large article does not require close attention from the time it starts until it is ready to be completed. This involves a great improvement in the article itself and a very important saving in time and expense of labor. The invention involves the means for accomplishing these results and certain details of construction and combinations of parts as will appear.

Reference is to be had to the accompanying drawings, in which—

Figure 1 is a perspective view of a sewing machine of well known type with a preferred embodiment of this invention shown as applied thereto and in a form for sewing square or rectangular box covers, and

Fig. 2 is a similar view showing it from another angle.

Although a considerable portion of the sewing machine is shown in Fig. 1 that does

not constitute a part of this invention and 55 will not be described in detail. It can be applied to many types of sewing machines having a needle feed as for example that shown in Patent No. 786,410 of April 4, 1905. The only parts necessary to be mentioned are the work rest 10 and the needle 11. The needle in this type of machine reciprocates vertically and the work rest is located according to the present invention at an inclination so that the edge of the 60 article to be sewed can be placed flat on the same and the article held in inclined position. In this way the seam sewed will be an inclined one passing through the edge of the side of the article and the adjacent edge of 65 the end or bottom thereof so as to attach the two together. It is to be understood that in ordinary practice the article is held in exactly this position by hand, the work rest 10 being well known in this industry. 70

In order to avoid the necessity for hand-manipulation of the article to be sewed I have provided a block 12 which fits within the article and supports it positively. The article is shaped up in any of the ordinary 80 ways known in this industry and secured to this block by any of any usual securing means that are well understood. The block then rests on the work rest 10 in such position that the article is held exactly in its 85 usual position.

In order to guide the article and have it always in the right position even when corners have to be turned, as in the article shown in Fig. 1, this block is provided with 90 a shaft 13 fixed to it and projecting normally from its center. The block is adjustable on the shaft by reason of being secured to it by screw threaded engagement. A normally tight fit is desirable. At the 95 other end of this shaft is a block 14 shaped exactly like the block 12.

On a fixed surface near the machine is placed a support 15 for holding and guiding the shaft 13. In the form shown in Fig. 1 100 this is provided with a supporting and guiding surface 16 parallel with the slanting upper surface of the rest 10 and having a guiding surface 17 at right angles thereto. The edge of the block 14 rests on the surface 16 105 while the flat rear side of the block 14 rests against the surface 17. Owing to the inclined position of the shaft gravity holds it

against these surfaces and thus they constitute means for limiting the position of the work.

In the operation of the device the operator 5 places the parts in the position indicated in Fig. 1 and starts the machine. It will sew a straight seam in the usual way, the ordinary feed of the sewing machine forcing the block 12 to move along as the seam progresses. Inasmuch as the block 14 is 10 comparatively light and is rigidly attached to the block 12 it also will move along the surfaces 16 and 17 and keep the shaft 13 in proper relative position of course. In other 15 words, as the shaft 13 rises at its upper end on account of sewing around the corner its lower end is caused to rise on account of the block 14 turning with the block 12. This keeps the parts in proper position so that 20 there will be no change in the angle of the sewing no matter whether the seam is straight or subjected to changes in direction. The operator holds the parts down on their guiding surfaces and the article 25 always retains the correct position.

In the form shown in Fig. 2 the parts are substantially the same except that the block 22 is cylindrical because the article to be sewed in this case is cylindrical. The shaft 30 23 is fixed to the block 22 as in the other case. In this case, the entire sewing operation is on a circular surface and the entire motion of the device is one of rotation. Therefore I have provided a support 25 35 fixed on the bench for example, and on this is a pivot shaft 26 on which is pivoted a block 27. This block 27 has a bearing for the shaft 23 so that the latter turns therein. During the entire operation in this case the 40 shaft 23 merely turns without changing its position because the center of the block 22 must remain stationary. As in Fig. 1 the block is held down on the work rest 10, by hand the operator grasping the shaft 23 to 45 steady the work. This shaft constitutes a handle for manipulating the work.

The reason for pivoting the block 27 is to provide an easy way for moving the work back from the machine and also to provide 50 and adjustment in case the machine is to be used to sew an article of a different diameter. This adjustment can be called entirely automatic because the circular block is attached centrally to the end of the shaft 55 23 and the work lowered on the work rest which will leave the parts in proper position no matter what the diameter of the article may be.

I have used this invention in practice and 60 found that it saves a great deal of labor and time, because it is easier to get the work into proper position and because it is no longer necessary for the operator to exert so much force to keep the work accurately

in place, and the amount of spoiled work 65 is very greatly reduced. A comparatively unskilled operator can produce about three times as much work as a skilled one by the old hand method. It is also a great advantage because the work is absolutely uniform 70 and there are no variations in the direction of the stitches.

Although I have illustrated and described only two forms of the invention I am aware 75 of the fact that other modifications can be made therein by any person skilled in the art and that it can be applied to other types of sewing machines without departing from the scope of the invention as expressed in the claims. Therefore I do not wish to be 80 limited in these respects, but what I do claim is:—

1. The combination with a sewing machine having a work rest and adapted to sew a corner seam, of a block fitting within 85 the work and adapted to rest on the work rest, a shaft projecting from the block, a block on the other end of said shaft having the same shape as the first named block and similarly located, and a support having a 90 surface which the second block freely engages for supporting and guiding the second block and controlling the position of the work.

2. The combination with a sewing machine 95 having an inclined work rest for receiving the outer edge of an article to be sewed, of a block having a non-circular surrounding edge, shaped to fit within the article to be sewed, and means for locating 100 said edge of the block in inclined position on the work rest and allowing it to turn thereon about an axis substantially parallel with said inclined surface of the work rest, said means having two surfaces at an angle 105 to each other for keeping the block in the same position relative to the work rest throughout the sewing of the seam.

3. The combination with a sewing machine having an inclined work rest, of a 110 block adapted to fit snugly within the article to be sewed so as to partake of its motions, and means for locating the block in inclined position on the work rest and allowing it to turn thereon, said means comprising an inclined surface constituting a 115 limiting means for limiting the motion of the block and article down the inclined surface of the work-rest, the block being held toward it by hand.

4. The combination with a sewing machine having a work rest and adapted to sew a corner seam, of a block fitting within the work and adapted to rest on the work rest, a shaft fixed to the center of the block, and a support fixed in position having a flat guiding surface thereon for the end of said shaft for holding the shaft in such position 125

as to permit the block to turn as the sewing proceeds and keep it at the proper angle on the work rest.

5. The combination with a sewing machine having a work rest and adapted to sew a corner seam, of a block fitting within the work and adapted to rest on the work rest, a shaft projecting from the block, a block on the other end of said shaft having 10 the same shape as the first named block, and a support having an inclined surface on which the second block rests, said surface constituting means for holding the shaft in such position as to permit the blocks to turn 15 as the sewing proceeds and keep the first named block at the proper angle on the work rest.

6. The combination with a sewing ma-

chine having a work rest and adapted to sew a corner seam, of a block fitting within 20 the work and adapted to rest on the work rest, a shaft projecting from the block, a block on the other end of said shaft having the same shape as the first named block and similarly located, and a support having an 25 inclined surface on which the second block rests at its edge and also an inclined surface against which the flat end of said second block rests, the first named surface being substantially parallel with the surface 30 of the work support, and the second surface perpendicular thereto.

In testimony whereof I have hereunto affixed my signature.

FREDERIK E. KNOBLOCK.
